SERVING SPOON

Arthur Salm, Chicago, Ill., assignor to Arthur Salm Inc.,
Chicago, Ill., a corporation of Illinois

Application July 18, 1955, Serial No. 37,011

Term of patent 14 years

(Cl. D54—12)

Fig. 1 is a front view of the serving spoon showing my new design; and

Fig. 2 is a side elevational view thereof.

I claim:

The ornamental design for a serving spoon, substantially as shown.
